UNITED STATES PATENT OFFICE.

JOHN T. PINE, OF NEW YORK, N. Y.

STEAM-HEATING APPARATUS.

SPECIFICATION forming part of Letters Patent No. 403,287, dated May 14, 1889.

Application filed May 12, 1888. Serial No. 273,690. (No model.)

To all whom it may concern:

Be it known that I, JOHN T. PINE, of the city and State of New York, have invented an Improvement in Steam-Heating Apparatus, of which the following is a specification.

In a steam-heating apparatus it is usual for the water of condensation to run back into a vessel or reservoir, from which such water is pumped back to the generator or into a reservoir, and in apparatus of this character, and also in feeding the water to steam-boilers, the supply of steam to the engine of the steam-pump has been regulated according to the height of water in the vessel or reservoir receiving the water of condensation. I make use of any ordinary steam-pump, and the steam to the engine of the pump is regulated by a valve controlled by a piston within a cylinder separate from the reservoir into which the water of condensation passes.

In instances where the supply of steam to the engine has been regulated by a float such float is liable to leak or to become injured and unreliable in operation. In consequence of using a vessel that is separate from the reservoir I am enabled to employ a cup-leather piston for the water to act upon, because such water remains at or about the temperature of the atmosphere, whereas if the cylinder and piston were within the reservoir they would be exposed to the heat of the water of condensation that would quickly injure the cup-leather packing.

In the drawings, Figure 1 is an elevation of the pump and a section of the cylinder containing the moving piston, and Fig. 2 is a section of the valve made use of for admitting steam to the engine.

The steam-cylinder C, valve-chest H, piston-rod D, pump B, and air-vessel D' are of ordinary construction, and the water of condensation which runs into the receiving-pipe A or into a reservoir of any suitable size, as indicated by the dotted lines, is drawn off by the pump through the pipe F, and from the pump B the water is forced through the pipe E into the boiler, generator, or holder of any desired character.

The cylinder M is connected by a pipe, I, preferably with the bottom of the reservoir or pipe A, and within this cylinder M is a piston,

N, sliding freely within such cylinder M and preferably provided with a cup-leather packing, and there is a rod, r, rising from the piston N and connected by a chain, w, to the lever m, that regulates the steam-valve. It is preferable to pass the chain w over the pulleys a, and the weight n upon the lever m is adjustable, so that it may balance, or nearly so, the piston N; hence when the water accumulates within the reservoir or pipe A it also rises in the cylinder M and lifts the piston N and allows the lever M to descend and supply more steam to the engine and cause such engine and pump to work faster, and when the water descends in the reservoir or pipe A it also descends in the cylinder M, and the piston N moves downwardly and by the chain w gives motion to the lever m and steam-valve to lessen the quantity of steam passing to the engine and cause the pumping-engine to run more slowly.

The steam-valve K is within a suitable case, I, and the steam-valve is balanced, in consequence of being made of the two valves a a, 75 upon the stem b, and the valves close upon the valve-seats e e, and there is an arm, f, projecting from the axis g of the lever m, which arm f passes through an eye in the stem b, and there is a packing around the axis g, so 80 that the same is made steam-tight, but is free to turn with but little friction, and this construction renders it unnecessary to make use of any packing around the valve-stem b.

I make use of a pressure-gage, R, connected 85 by a branch pipe and cock to the pipe L, and this pressure-gage indicates the pressure of the column of water within the pipe L and cylinder M, and in case of accident to any part of the apparatus this gage will indicate 90 any increase in the water-level of the apparatus.

In consequence of the steam-valve being balanced and there being but little friction upon the parts that actuate the valve said 95 valve will be moved by a slight change in the water-level, and there is but little friction between the cup-leather packing of the piston N and the cylinder M, and this cup-leather packing will not be exposed to heat, as there will be 100 no circulation of water into or out of the cylinder M except that which results from the

rise and fall of the water-level, as the hot wa-
ter of condensation runs into the pipe or res-
ervoir A, and is thence taken to the pump B:

I claim as my invention—

5 1. The combination, with the steam-pump,
steam-supply pipe, and valve for the same, of
the reservoir for receiving the water of con-
densation, the separate cylinder M, and the
10 pipe L, leading from the same to the res-
ervoir, and a piston within the cylinder M, and
a connection from the same to the lever of the
steam-valve, substantially as and for the pur-
poses set forth.

2. The combination, with the receptacle for
15 the water of condensation, of a pump and con-
necting-pipe, a steam-engine, and a valve for
controlling the supply of steam for the same,
a separate cylinder, M, and a pipe, L, connect-

ing from the cylinder to the reservoir, a cup-
leather piston within the cylinder, and a chain 20
connecting the piston-rod to the lever of the
steam-valve, substantially as set forth.

3. The combination, with the reservoir or
vessel for the water of condensation, of a
steam-pump, a pipe connecting the reservoir 25
to the pump, a steam-supply pipe and valve
for the engine, the separate cylinder M, and
the pipe L, connecting the cylinder to the res-
ervoir, a piston within the cylinder, a piston-
rod, a chain passing over the pulleys, and the 30
lever for moving the steam-valve, substan-
tially as set forth.

JOHN T. PINE.
